UNITED STATES PATENT OFFICE.

HENRY ENEU JOHNSON, OF LANSDOWNE, PENNSYLVANIA.

DESIGN FOR A COMBINED STAND AND CLOCK-CASING.

47,919.

Specification for Design.

Patented Oct. 5, 1915.

Application filed April 19, 1915. Serial No. 22,512. Term of patent $3\frac{1}{2}$ years.

To all whom it may concern:

Be it known that I, HENRY ENEU JOHNSON, a citizen of the United States, residing at Lansdowne, in the county of Delaware and State of Pennsylvania, have invented a new, original, and ornamental Design for a Combined Stand and Clock-Casing, of which the following is a specification, reference being had to the accompanying drawing, forming part thereof.

The figure is a perspective view of a combined stand and clock casing, showing my new design.

I claim:

The ornamental design for a combined stand and clock casing, as shown.

HENRY ENEU JOHNSON.
